UNITED STATES PATENT OFFICE.

FRANK JOHNSON, OF BOSTON, MASSACHUSETTS.

DRYING APPARATUS.

No. 798,345.

Specification of Letters Patent.

Patented Aug. 29, 1905.

Application filed October 10, 1904. Serial No. 227,831.

To all whom it may concern:

Be it known that I, FRANK JOHNSON, a citizen of the United States, and a resident of Boston, county of Suffolk, and State of Massachusetts, have invented an Improvement in Drying Apparatus, of which the following description, in connection with the accompanying drawings, is a specification, like letters on the drawings representing like parts.

10 The present invention relates to a drying apparatus, and is designed especially for laundries, to be used in connection with laundry-machines, and to receive therefrom the articles which have been washed and rinsed, 15 the feed of the articles through the drying-machine being automatic, so that the articles are delivered therefrom thoroughly dried.

The machine embodying the invention comprises a closed chamber of sufficient size to 20 contain a number of guide-rolls, the said chamber being heated, preferably, by means of steam-coils and also supplied with air which is caused to circulate through the chamber and carry away the moisture. The articles 25 to be dried are carried through the chamber by means of endless aprons, there being two of such aprons running over the rollers back and forth through the chamber, and the articles fed between the aprons are thus caused 30 to travel a considerable distance within the chamber, being finally delivered from between the last pair of rolls. The aprons serve to keep the articles flat between them and are made of pervious material, so as to admit of 35 a circulation of the heated air through them and through the article between them.

Figure 1 is a side elevation of the drying apparatus embodying the invention. Fig. 2 is a vertical section thereof. Fig. 3 is a transverse section taken on line x^3 of Fig. 1 looking 40 toward the right, and Fig. 4 is a horizontal section through the upper part of Fig. 3.

The drying-chamber a , the walls of which may be made of any suitable material, such 45 as wood, is substantially closed and is supplied with heat from any suitable source, the interior of the chamber being shown as provided with steam-coils b^2 , which are fed from a steam-pipe b , extending into the chamber a , 50 the steam passing through the coils to an outlet-pipe b^3 . In order to feed the articles through the chamber a to be subjected to the heat therein, the apparatus is provided with carrying-aprons c and d , each of which is 55 shown as an endless apron, the apron c passing over a roll c^2 and a roll c^3 , both of which,

as best shown in Fig. 2, are at the outside of the chamber a , and back and forth over a series of rolls e , which are mounted within the chamber. The apron d similarly passes over a roll d^2 , which is adjacent to the roll c^2 , and thence back and forth parallel to the apron c , over the rolls e within the chamber. The walls of the chamber a are provided with slots a^2 , a^3 , and a^4 for the apron c and slots a^5 and a^6 for the apron d , the apron c also passing through the slot a^5 .

An article fed between the two aprons c and d , where they pass over the rolls c^2 and d^2 , will be carried downwardly through the slot a^5 and back and forth between the aprons over the rolls e , thus traveling back and forth in the chamber a and being retained therein for a considerable length of time, being finally delivered between the uppermost right-hand rolls e upon the apron c and carried out of the chamber through the opening a^2 . The chamber is shown as provided with a guide a^6 adjacent to the opening a^2 , which guide projects inward over the apron c to catch the dried article as it is delivered and guide it out of the chamber a through the opening a^2 .

In order to obtain the best distribution of the heat, the steam-coils b^2 are shown as projecting from the pipe b transversely across the chamber a substantially in the planes of the axes of the rollers e , so that the coils project between the loops of the aprons. Thus the aprons c and d and the articles between them travel successively over the steam-coils b^2 , becoming subjected to the heat therefrom to the best advantage.

The air heated by the steam-coils b^2 , above described, is kept in circulation by means of a suitable air-forcing device, herein shown as a blower f , having a suction-pipe f^2 , which leads from the top of the chamber a , and a discharge-pipe f^3 , which leads into the said chamber, the said pipe f^3 in the construction shown communicating directly with a reservoir f^4 at the top of the chamber, which reservoir is provided with a pipe f^5 , communicating with a series of distributing pipe systems f^6 , there being one of such distributing systems for each loop of the aprons.

The main drying-chamber a is not tightly closed at the bottom, so that it will receive air which is drawn by the blower f through the pipe f^2 after passing upward over the steam-coils b^2 and thereby becoming heated, the same heated air being delivered through the pipe f^3 into the reservoir f^4 and thence

to the interior of the chamber. In practice the chamber may be built independently of the floor on which it rests, there being sufficient leakage to supply all the air that is 5 needed, although the chamber is substantially closed, so as to prevent undue dissipation of the heat utilized in the drying process. As herein shown, each of the distributing pipe systems f^6 consists of a plurality of branches 10 f^7 , which communicate with the pipe f^5 and are closed at their ends and provided with perforations f^8 at the upper side. These perforations are gradually increased in size from the top to the bottom of the chamber, the perforations in the top member of the pipe system, where the air-pressure is greatest, being comparatively small, while those in the bottom member of the pipe system, where the temperature has become decreased, are comparatively 15 large. In the construction shown these distributing pipe systems f^6 rest directly upon the steam-coils b^2 and are below the lower apron c , the air thus being reheated by the coils and blown upward against the under side of 20 the apron by the action of the forcing apparatus f . As the heat naturally rises in the chamber, moreover, so that the temperature of said chamber is highest at the top thereof, the air becomes more or less heated in the 25 reservoir f^4 , so that the direct contact of the steam-coils with the distributing-pipes acts upon air which is already partially heated, so that the air delivered from said distributing-pipes is very hot. The chamber a is further provided at the top with a fan g , herein shown as mounted on a spindle having a vertical bearing in the top of the chamber, and a pulley g^2 , whereby it may be driven, this fan assisting in the agitation of the air within the 30 chamber and tending to distribute the current of air throughout the same, so that all parts of the aprons and the articles carried by the aprons are equally subjected to the currents of heated air. 35

40 The rolls e are shown as mounted on shafts e^2 , extending through the end walls of the chamber a and having bearings in standards h , the said shafts being provided with sprocket-wheels e^3 , so that all the rolls can be driven by means of a sprocket-chain e^4 . In the construction shown said sprocket-chain e^4 is driven from a sprocket e^5 on the axis of the roll d^2 , which is arranged to be driven by the pulley d^3 , and is provided with a gear d^4 , 45 which meshes with a gear-wheel c^4 on the roll c^2 , so that both aprons are positively driven by the rotation of the rolls c^2 and d^2 as well as by the rotation of the rolls e inside the chamber.

50 The apparatus is herein shown as mounted adjacent to a washing-machine A , which is provided with squeeze-rolls A^2 , between which the articles are delivered to the drying-machine, and the said squeeze-rolls may 55 be caused to rotate in any usual or suitable

way in connection with the mechanism which operates the drying-machine, as by the sprocket-chain d^6 .

In order to keep the aprons from running off the rolls e endwise, the apparatus is shown as provided with automatic centering devices i and j , which coöperate, respectively, with the aprons c and d , which centering devices may be of any suitable or usual construction not herein shown or described in detail, since they form no part of the present invention. 75

The articles are fed in any suitable way into the space between the rolls c^2 and d^2 , where they become engaged between the traveling aprons c and d , which draw the articles into the chamber a and carry them back and forth therein over the steam-coils b^2 , so that they are subjected to the heated air, which is kept in circulation by the air-forcing apparatus, and are finally delivered 85 between the two upper right-hand rolls, which are shown as slightly separated from each other, so that the aprons are not in contact. The articles delivered at this point pass down the apron c and out through the 90 opening a^2 .

As will be seen from the foregoing description, the air is directed against the articles to be dried in large jets at the bottom, where the temperature is lowest and the goods wet, the size of the jets diminishing as the higher temperatures are reached and the moisture more extracted. Furthermore, the direct action of the air-jets on the previous aprons and the articles between them 100 is such as to keep the articles agitated and to prevent them from becoming wrinkled in drying.

What I claim is—

1. A drying apparatus comprising a drying-chamber, a series of rollers within said chamber and arranged at opposite sides thereof; endless aprons extending together over said rollers; means for rotating the said rollers to cause the said aprons to travel; and means for subjecting said aprons to jets of air from sources adjacent thereto, said jets being transverse to the direction of travel of the aprons, substantially as described. 105

2. In a drying apparatus, a drying-chamber provided with a series of rollers at opposite sides thereof; steam-coils projecting across the chamber adjacent to said rollers; means for rotating the said rollers; two endless aprons extending together over the said rollers 110 to receive and carry the articles to be dried through the chamber, and air-pipes located adjacent to the steam-coils, and provided with jet-orifices through which the air is directed toward the aprons, substantially as described. 115

3. In a drying apparatus, a substantially closed drying-chamber; two endless aprons extending into the said chamber; rollers within the said chamber to carry said aprons; steam-heated coils within the chamber between the 120 125 130

loops formed by the rollers in the aprons, and means for directing jets of air against the aprons in a direction transverse to the direction of travel thereof.

5 4. In a drying apparatus, a drying-chamber, endless aprons to receive and carry the articles to be dried between them; means for driving said aprons through the chamber; and sources of compressed air adjacent to said aprons and 10 provided with jet-orifices opening in a direction transverse to the direction of travel of the aprons.

5. In a drying apparatus, the combination with a drying-chamber; of means for causing 15 the articles to be dried to be carried flat through said chamber; and means for directing blasts of heated air against said articles in a direction transverse to the direction of travel thereof, substantially as described.

20 6. In a drying apparatus, the combination with a drying-chamber; of an endless carrier for the articles to be dried arranged to travel back and forth through said chamber; heating appliances adjacent to said traveling carrier; and sources of air provided with jet-orifices and located adjacent to said heating 25 appliances, substantially as described.

7. In a drying apparatus, the combination with a drying-chamber; of a pair of endless 30 belts of pervious material arranged to travel back and forth through said chamber and to carry the articles to be dried between them; heating-coils between adjacent loops of said endless belts; air-ducts between said heating-

35 coils and the part of the endless belts above said coils, said air-ducts being provided with jet-orifices opening in a direction transverse to the direction of movement of the endless belts; and means for supplying said air-ducts with air under pressure. 40

8. In a drying apparatus, the combination with a drying-chamber; of a pair of endless belts of pervious material arranged to travel back and forth through said chamber and to carry the articles to be dried between them; 45 heating-coils between adjacent loops of said endless belts; air-ducts between said heating-coils and the part of the endless belts above said coils, said air-ducts being provided with jet-orifices; means for supplying said air-ducts 50 with air under pressure; and an agitating device, such as a fan, also contained within said chamber, substantially as described.

9. In a drying apparatus, a drying-chamber; means arranged in horizontal loops for feeding the articles to be dried through said chamber; an air-duct below each loop; and jet-orifices in the upper side of each air-duct, the orifices in each duct below the uppermost duct being greater than those in the ducts 60 above.

In testimony whereof I have signed my name to this specification in the presence of two subscribing witnesses.

FRANK JOHNSON.
